RETORT BURNER

Thomas W. Hunter, Pasadena, Calif.

Application March 27, 1933, Serial No. 662,977

3 Claims. (Cl. 158—66)

This invention relates to a burner, and particularly pertains to a retort fuel burner.

It is a principal object of the present invention to provide a fuel burner of simple and compact construction and which utilizes relatively inexpensive liquid fuels and brings about their combustion in a manner to insure that maximum amount of heat can be obtained from the burner and can be created over a maximum area without the formation of smoke or the formation or deposit of soot, said results being accomplished by a simple burner structure which does not require continued attention or constant care and regulation and which in fact does not require that the burner be maintained in a true vertical position.

The present invention contemplates the provision of a main burner bowl, a diffusing shell disposed therein to distribute the liquid fuel evenly around its entire circumference, and a combustion ring by which a supply of air is mixed with vapors before reaching the combustion chamber, and which ring will also act to direct the course of the flames resulting from the combustion and protect the flame from being extinguished by any excess draft which might occur in the burner.

The invention is illustrated by way of example in the accompanying drawing, in which:

Figure 1 is a view and plan showing the complete burner with which the present invention is concerned;

Figure 2 is a view in transverse central vertical section through the burner as seen on the line 2—2 of Figure 1; and

Figure 3 is a view in side elevation showing the burner assembled with a flue and with parts of the flue broken away for convenience.

Referring more particularly to the drawing, 10 indicates a liquid fuel supply pipe which projects horizontally into a threaded boss 11 of a burner bowl 12. This bowl is in the form of a conical shell having a downwardly and inwardly inclined base 13 converging at the apex of the bowl in a fuel well 14. The upper and outer marginal edge of the burner bowl 12 is formed with an outwardly and upwardly flaring lip 15 over which a supply of air passes in a manner to be hereafter described. Positioned within the 50 bowl is a diffusing shell or cone 16, the outer face of which substantially agrees with the inner face 13 of the bowl 12 but is spaced therefrom by a plurality of ribs 17. These ribs are attached to the outer face of cone 16 and extend longitudinally of the face in substantially

unbroken lengths from a point just above the upper rim of well 14 to a point where they rest snugly against the inner face of the bowl 12. These ribs 17 are uniformly spaced around the circumference of the cone and are preferably spaced close together to obtain maximum efficiency, the space 18 between the outer face of the cone 16 and the inner face 13 of the bowl 12 thus provides a series of longitudinal grooves or passageways for the vapors. The principal purpose of these ribs is to confine the fuel vapors, being generated in the bowl, in such a manner as to compel the vapors to travel upwardly along the courses defined by the passageways 18 occurring between the ribs 17 and to thus prevent the vapors from drifting from their course as might otherwise be the case if the burner structure assumed a position out of plum. This construction insures a uniform flow of vapor to every part of the entire circumferential length 20 of fuel throat 21, whether the burner is level or not.

The diameter of the base portion 19 of the cone 16 is somewhat less than the diameter of a vertically-walled counterbore 20 which occurs around the upper opened end of the burner. These differences in diameter cause an annular feed space 21 to be formed between the edge of the base 19 and the face 20 of the bowl 12 and through which space liquid fuel is fed into the 30 air throat 21 and thence into the combustion chamber which is the space occurring between the base portion 19 and an annular tubular flange 32 projecting from the top of cone 16. The chamber is further defined by the lower ends 35 of teeth 28 on ring 26. The base 19 of the shell lies in a plane substantially at right angles to the liquid fuel throat 21 and is formed with an annular tubular flange 22. This flange projects vertically from a plane of the base 19 and circumscribes a generating or priming well 23. Supported above the outwardly flaring lip 15 of the bowl 12 is a ring 24 which has an inclined body portion 25 and a vertically extending lip at its upper end as indicated at 26 to which is 40 attached a flue pipe 40 indicated in Fig. 3 of the drawing and which pipe it is customary to provide to give the required draft to a burner of this type. The inclined body of the ring extends downwardly and inwardly and overhangs the lip 45 50 55 55 of the bowl. The angle of the under face of the portion 25 is slightly greater relative to the horizontal than the angle of the upper face of the lip 15, thus forming an annular inwardly and downwardly converging throat through

which air passes directly over fuel throat 21 and base 19 of the shell 16. Resting upon the upper face of the inclined portion 25 of ring 24 is a combustion ring 26 which has an upwardly and outwardly flaring portion overlapping the inclined portion of ring 24 and projecting downwardly through the central opening of ring 24 where it is formed with a cylindrical face substantially fitting the opening in the ring, the angle of the lower face 27 of the combustion ring substantially agreeing with the angle of the portion 25 of ring 24 and is a continuation thereof. Extending downwardly from the face 27 of the combustion ring 26 is a plurality of radial vanes or teeth 28 which are tapered in thickness toward their lower end, and the lower edges of which as indicated at 29 are inclined to agree substantially with the angle of the upper face of the lip 15. The outer vertical edges 30 of these teeth are substantially in vertical alignment with the outer circumferential edge of the fuel throat 21 as defined by the face 20 of the fuel bowl 12. The vanes 28 thus act to divide the air which might travel into the air throat 31 between the lip 15 and the face 25 of ring 24 into a plurality of radially moving streams or jets which are directed downwardly and inwardly across the fuel throat 21. The vanes 28 will also act to prevent the fuel vapors from igniting at the throat 21. They act to create a small eddy current at the lower end of each vane which acts as a pilot or tongue of flame slightly protected from the main force of the draft and thereby prevents the flame from being blown out by the draft. The vanes make it possible for a large volume supply of air to be delivered to the burner in an unrestricted manner until it has passed across the fuel throat after which the air will be divided into jets having a greater velocity. This prevents back burning of the fuel vapor at or outside of the fuel throat. The action of the air passing in through the spaces between the vanes and beyond the fuel throat also insures a proper mixture of air and fuel vapor before combustion takes place. The ring 24 is spaced from the fuel bowl by tubular spacing members 32 through which screws 33 extend and by which the members are held in their assembled position. These screws are the only fastening elements required in the burner since the other parts are readily nested together and may be instantly separated for cleaning or other purposes.

In operation of the present invention a constant supply of liquid fuel is delivered to the burner through the pipe 10. This supply may be regulated by any suitable manual or automatically controlled regulating means. The liquid fuel will fill the well 14 and then partially fill the space 18 between the bowl and the shell 16 where vaporization will take place. The fuel will thus flow upwardly around the shell 16 and into the annular fuel throat 21, which throat extends in an unbroken line entirely around the burner. The burner may be ignited by placing combustible liquid or other materials within the priming cup 23 of the shell 16, after which a draft will be created to draw air inwardly through the air throat 31 and downwardly over the fuel throat 21 to the combustion chamber where the shell is heated. After the entire structure is heated the liquid fuel which fills into the space 18 will vaporize and escape into the air duct 31 at the fuel throat 21 and is carried upwardly by the draft of incoming air through throat 31 to the

flue. This fuel may be ignited at the fuel throat, after which the plurality of jets of air will pass downwardly across the throat as divided and directed by the vanes 28 and will then pass upwardly through the member 26 as directed by the vertical flange 22. The result will be that a uniform combustion will take place owing to the thorough mixture of air and vapor before reaching the combustion chamber and an annular flame will be created entirely around the vertical flange 22 of the shell 16. This arrangement insures that a maximum heat efficiency may be obtained by the use of low grade oils which are commonly considered undesirable for perfect combustion but which have decided advantages due to their availability and cheapness.

The upper edge of the bowl 12 and the ring members 24 and 26 will provide an annular throat which leads inwardly and downwardly across the annular orifice 21. This orifice or fuel throat occurs between the wall of the bowl 12 adjacent its mouth and the upper edge of the cone 16. The flue pipe will cause a draft of air to be created inwardly beneath the ring members 24 and 26, and then upwardly through the ring 26. It will be evident that in the event an attempt was made to ignite fuel in the orifice 21 the excessive volume of air drawn inwardly by the draft would extinguish this fuel. In order, therefore, to provide a burner which will have proper combustion and that insures ignition of the fuel will continuously take place, the throat occurring between the bowl of the burner and the ring 26 is divided circumferentially by a plurality of radial teeth. These teeth are shown as having appreciable width so that an air inlet throat of the burner will in effect be divided into a plurality of radial passageways through which air may flow inwardly and intermediate spaces occupied by the teeth. The result will be that the air passing inwardly between the teeth will in effect form jets between which relatively dead air spaces will occur as substantially represented by the cross sectional area of the teeth 28. The collective cross sectional area of the teeth diminishes the open space of the throat through which air may flow and thereby reduce the volume of air, while the provision of the teeth having an appreciable sectional area tends to shield the space at the inner ends of the teeth and tends to create a dead air space between the inflowing jets of air. In these spaces the fuel vapor will burn without being extinguished, and with a combustion which insures that the parts will be maintained clear and free of carbon.

It will also be evident that the device here disclosed is quite simple in construction, may be readily assembled or dismantled, and will operate with efficiency to supply heat to a relatively large area.

While I have now shown the preferred form of my invention, as now known to me, it will be understood that various changes may be made in combination, construction, and arrangement of parts by those skilled in the art without departing from the spirit of my invention as claimed.

Having thus described my invention, what I claim and desire to secure by Letters Patent is:—

1. An oil burner of the retort type comprising a bowl, a cone nested within the bowl and spaced therefrom, said bowl and cone forming a circumferentially extending orifice in a horizontal plane adjacent the mouth of the bowl, means for de-

livering liquid fuel to the bowl to flow upwardly in the space between the bowl and cone and to pass outwardly through the annular orifice as a fuel vapor, a ring disposed above said bowl and cone in spaced relation thereto and spanning the annular orifice throughout its circumference, a flue disposed above said ring whereby a draft will be created inwardly beneath the ring and across the annular fuel orifice and upwardly through the 5 ring, and a plurality of teeth arranged in equal spaced relation to each other and dependent from the under face of the ring and projecting below the upper edge of the bowl, said teeth extending radially across the annular orifice and spaced a 10 distance thereabove, the teeth having appreciable width whereby the inflowing draft of air will be divided into a plurality of inwardly and radially moving air streams separated by relatively dead air spaces occurring between the streams of air 15 and adjacent the inner ends of the teeth.

2. A retort burner comprising a bowl, a member telescoping thereinto and spaced therefrom to form an annular orifice at the mouth of the bowl, means for delivering liquid fuel to the bowl to flow upwardly in the space between the bowl and the telescoping member, an outwardly and upwardly flaring flange formed around the mouth of the bowl from the plane of the annular orifice, a 20 downwardly and inwardly inclined ring spaced from the lip of said flange and lying substantially parallel thereto to form an annular inlet throat across the annular orifice, a flue member mounted upon the top of said ring to create a draft inwardly through the throat and upwardly through the flue, and a toothed ring carried by 25 the last named ring and extending downwardly and inwardly beyond the inner lip of the inclined ring, said toothed ring being formed with a plurality of downwardly projecting teeth equally spaced from the end face of said ring and ex-

tending radially across the annular orifice and thereabove, said teeth providing passageways between them along which a proportion of the air from the annular air inlet may be conducted across the annular fuel orifice from the area exterior of said orifice to an area interior of said orifice, whereby the air passing through said passageways between the teeth will co-mingle with the fuel from the orifice within the area circumscribed by the fuel orifice.

3. A retort burner comprising a bowl, a member telescoping thereinto and spaced therefrom to form an annular orifice at the mouth of the bowl, means for delivering liquid fuel to the bowl to flow upwardly in the space between the bowl and the telescoping member, an outwardly and upwardly flaring flange formed around the mouth of the bowl from the plane of the annular orifice, a downwardly and inwardly inclined ring spaced from the lip of said flange and lying substantially 20 parallel thereto to form an annular inlet throat across the annular orifice, a flue member mounted upon the top of said ring to create a draft inwardly through the throat and upwardly through the flue, and a plurality of teeth supported by the 25 ring and arranged in spaced relation to each other circumferentially of said ring, said teeth projecting downwardly into the throat and radially thereof and having inner ends of appreciable width occurring within the area circumscribed by the orifice whereby the air flowing inwardly through the throat will pass around the opposite sides of the teeth to divide the inflowing air current into a plurality of inwardly and radially moving air streams separated by relatively 30 dead air spaces occurring between the streams of air and adjacent to said inner ends of the teeth.

THOMAS W. HUNTER.
